Patented Feb. 26, 1924.

UNITED STATES PATENT OFFICE.

JOHN O. WILLSON, OF ST. JOE, ARKANSAS, ASSIGNOR TO HELENA UNIT HOOP-HEAD CO., OF HELENA, ARKANSAS, A CORPORATION OF ARKANSAS.

COMBINED BARREL END AND HOOP.

Application filed November 25, 1921. Serial No. 517,526.

To all whom it may concern:

Be it known that I, JOHN O. WILLSON, a citizen of the United States, residing at St. Joe, county of Searcy, and State of Arkansas, have invented a new and useful Combined Barrel End and Hoop, of which the following is a specification.

This invention relates to a combined barrel end and hoop for use on slack barrels.

10 An object of the invention is to provide an improved metal barrel end and hoop formed in one integral structure, designed and adapted for use in connection with slack barrels specially, as distinguished from barrels for containing liquid. The invention is 15 designed and adapted particularly for use in connection with barrels adapted to contain such merchandise as lime, nails, staples and other heavy slack or piece merchandise, 20 as distinguished from liquids.

Another object of the invention is to provide a combined end and hoop arranged to function and cooperate with the barrel in the novel and efficient manner hereinafter 25 stated.

In the drawings,

Fig. 1 is a side elevation of a barrel having each end equipped with my improved combined end and hoop.

30 Fig. 2 is a sectional view showing important and essential features of the invention.

As shown, the combined barrel end and hoop is made from a circular plate formed 35 to provide a flat, circular end wall 1 arranged to fit tightly within the end of the barrel and provided with an integrally united hoop. The connection of the hoop with the end wall 1 is adapted, constructed 40 and designed to embrace and engage the untapered end of the barrel staves in such a way as to obtain new and useful results. The new and useful results obtained from the engagement mentioned comprise the 45 drawing and clamping of the staves of the barrel very close together. As shown the connection uniting the hoop 2 with the end wall 1 comprises a peripheral upwardly extended part or flange 3 having an arched 50 connection 4 with the hoop 2.

The construction and relationship of these portions of the device are such that the end wall 1 may pass into the end of a barrel, the staves of which are untapered 55 and are of equal thickness throughout their

length, as distinguished from barrels whose staves are tapered to provide the well known tapered chimes at the ends. The annular space between the flange 3 and the hoop 2 tapers upwardly slightly so that the radial 60 width of said space at the entrance thereto is greater than the radial width at the bottom thereof. The radial width of the space at the opening thereto is sufficient to receive the untapered ends of the barrel staves but the radial width of said space at the bottom thereof is somewhat less than the thickness of the barrel staves. Moreover, the parts of the device are proportioned with respect to the barrel for which it is intended so that it is necessary to tamp or drive or press the device to position when it is applied to the barrel. The proportion of the parts involves the relationship in which the hoop 2 will 65 compress, clamp and draw together and rigidly and firmly hold the ends of the barrel staves to dispense with the use of a number of separate hoops which has otherwise been required for slack barrels. As the device is forced to position by tamping or hammering the same or by applying pressure thereto, the ends of the barrel staves are clamped and compressed within the annular space 70 between the hoop 2 and the flange 3 (Fig. 2) in such a way as to form a tight closure 75 without the use of sealing or cementing substances.

After the device is applied to the barrel the hoop 2 is indented, as by means of a punch or other similar tool and thereby additionally secured to the barrel. The indentations 5 are formed at intervals, preferably by use of a V-shaped tool adapted for that purpose, by driving the tool against the hoop 2. This breaks the metal of the 80 hoops at the points at which the tool is driven, and forms angular projections 5, the points of which are driven into the compressed portions of the staves in substantial alignment with the end wall 1. In practice, 85 five or more of such indentations are formed around the hoop at approximately equal distances. No nails or other similar fastening devices are required or used.

I have found that the device constructed 90 and applied and used as herein disclosed is adapted for uses and purposes, particularly in connection with lime barrels, for which no other equally satisfactory and efficient device has been available. I have found this 95 105 110

to be so by complete investigation of the trade in which I am engaged, and I have also found that the herein disclosed device obtains all of its intended objects and purposes in a highly efficient and satisfactory manner. As a result of these experiences I state the fact to be that this invention meets an existing demand and want in a thoroughly satisfactory manner; and that other, but unsuccessful, attempts have been made to meet this demand and want.

Without restricting myself unessentially, what I claim and desire to secure by Letters Patent is:—

15 A barrel, comprising wooden staves of equal thickness throughout their length; a head stamped from sheet metal and formed with a central circular flat wall closing the end of the barrel body, a marginal exten-

sion of the central wall including an annular arch portion of the curved type, said arch portion having the walls thereof tapering inwardly, the space between the walls at the bottom of the arch being approximately the thickness of the barrel staves and the outer wall of the arch being extended to form a hoop; said arch and hoop being arranged to fit over the untapered ends of the staves and to be pressed thereon, thereby compressing the ends of the staves to form a seal between the staves and the arch portion of said extension; and retaining means formed in connection with the hoop for securing the head in position after it has been pressed to its seat on the ends of the barrel staves.

JOHN O. WILLSON.
